UNITED STATES PATENT OFFICE.

FRANK FESSLER, OF DES MOINES, IOWA, ASSIGNOR OF ONE-HALF TO C. E. ROWE, OF DES MOINES, IOWA.

OPERA-CHAIR.

1,247,385.

Specification of Letters Patent. Patented Nov. 20, 1917.

Application filed March 13, 1917. Serial No. 154,621.

To all whom it may concern:

Be it known that I, FRANK FESSLER, a citizen of the United States, and resident of Des Moines, in the county of Polk and State of Iowa, have invented a certain new and useful Opera-Chair, of which the following is a specification.

My invention relates to opera chairs, capable of adjustment for varying the positions 10 between rows of such chairs.

The object of my invention is to provide an opera chair so constructed and supported that the chair seat may be swung rearwardly, so that the total space from front to rear 15 occupied by the chair will not be materially increased, and yet the distance between the chair being operated and the row of chairs in front may be varied for leaving a greater or less space through which patrons of the 20 theater or the like may pass.

A further object is to provide such a chair so mounted that the seat and back may be swung or tilted from position where the back is inclined upwardly and rearwardly to position 25 where the back is substantially vertical, the lower part of the back being swung rearwardly for thereby allowing a greater space in front of the chair.

With these and other objects in view, my 30 invention relates to the construction, arrangement and combination of the various parts of the device, whereby the objects contemplated are attained, as hereinafter more fully set forth, pointed out in my claims, 35 and illustrated in the accompanying drawings, in which:

Figure 1 shows a side elevation of an opera chair embodying my invention, the dotted lines showing the chair in its rearward position.

Fig. 2 shows a front elevation of said chair, and

Fig. 3 shows a vertical, sectional view taken on the line 3—3 of Fig. 2.

In the accompanying drawings, I have 45 shown an illustration of one form of my opera chair, having the seat, which is indicated by the reference character 10, the arms 11 and the back 12.

I provide beneath the forward portion of 50 the seat a bracket 13 having forked, spaced, upwardly extending arms 14, pivotally secured to the bottom of the seat near opposite sides thereof, and near the forward portion 55 thereof, as illustrated in Figs. 1 and 2. At

its lower end the bracket 13 is provided with spaced, forked, arms 15, which are pivoted to the floor upon which the chair is supported.

Rearwardly of the bracket 13 is a bracket 60 16 having arms 14, similar to those already described, pivoted to the bottom of the seat rearwardly of the pivot points of the first arms 14 and near the side edges of the seat.

The bracket 16 is provided at its lower end 65 with arms 15, similar to those already described, and similarly pivoted to the floor.

It should be mentioned in this connection that the distance between the upper ends of the brackets 13 and 16 is substantially less 70 than the distance between the lower ends thereof, and that the total length of the bracket 16 from the chair seat to the floor is greater than the total length of the bracket 13 from the chair seat to the floor. 75

The bracket 13 is provided on its rearward surface with a rearwardly opening channel 17 closed at its ends.

Rotatably but non-slidably mounted on the bracket 16 is a bolt 18, extending forwardly and slightly downwardly. The forward portion of the bolt 18 is screw-threaded at 19. On the forward end of the bolt 18 is screwed an elongated socket 20, the forward end of which travels in the channel 17. 85

In the practical construction and operation of my improved opera chair, it may be noted that the back 12 may be arranged at any desired angle with relation to the seat 10. I have shown one arrangement of the 90 parts, in the drawings.

In the normal position of the chair, as shown in the drawings, the brackets 13 and 16 extend upwardly and forwardly from the floor, and the back 12 is inclined from its 95 lower end upwardly and rearwardly with relation to the floor.

The engagement of the forward end of the socket 20 with the lower end of the channel 17 prevents the chair seat from swinging 100 downwardly and forwardly beyond a certain predetermined position.

If a person is seated in the chair and someone attempts to pass in front of the person so seated, the person seated may push 105 the seat of his chair rearwardly to the position shown in dotted lines in Fig. 1. It will be noted that the seat and the lower portion of the back will swing rearwardly a considerable distance, but that the upper 110

end of the back moves rearwardly only a slight distance.

As the seat is swung rearwardly the brackets 13 and 16 move from their positions, shown in Fig. 1 in full lines, to their positions shown in dotted lines in said figure, extending upwardly and rearwardly from their lower ends, and the socket 20 swings upwardly in the channel 17 until it 10 engages the upper end of said channel, whereby the rearward and downward movement of the seat 10 is limited.

It will be seen that by adjusting the lower ends of the brackets 13 and 16 rearwardly 15 or forwardly on the floor 1, considerable variation in the positions and adjustment of the chair may be secured, and the socket 20 is adjustably mounted on the bolt 18 for accommodating and making possible such 20 adjustment and for causing the bolt 18 and socket 20 to serve as a limiting device in all positions of said adjustment.

The entire device is of very simple and inexpensive construction and permits the 25 rearward and forward swinging movement of the seat with very little inconvenience to the persons behind the seat being moved.

On account of the rearward position of the back 12 in the forward position of the 30 seat, it will be seen that the seat 10 may be moved rearwardly a considerable distance for allowing a space in front of the seat, and for reducing the total space from front to rear occupied by the seat by swinging 35 the back 12 from its rearward position to its substantially vertical position.

It will, of course, be obvious that the distance of the swing may be varied as may be desired.

40 I claim as my invention:

1. An opera chair having a seat and a back, a bracket pivoted to said opera chair seat near the forward end thereof, and designed to be pivoted to the floor, a second 45 bracket pivoted to said opera seat rear-

wardly of the upper point of attachment of the forward bracket, and designed to be pivoted to the floor, said brackets being of different lengths from the seat to their lower ends, a member secured to one of said 50 brackets and extending toward the other, and means on said other member for limiting the up and down movement of said member, said means comprising a channel having closed upper and lower ends. 55

2. An opera chair having a seat and a back, a bracket pivoted to said opera chair seat near the forward end thereof, and designed to be pivoted to the floor, a second bracket pivoted to said opera seat rearwardly of the upper point of attachment of the forward bracket, and designed to be pivoted to the floor, said brackets being of different lengths from the seat to their lower ends, a member secured to one of said 60 brackets and extending toward the other, and means on said other member for limiting the up and down movement of said member, said member being composed of two parts longitudinally adjustable. 65

3. An opera chair having a seat and a back, a bracket pivoted to said opera chair seat near the forward end thereof, and designed to be pivoted to the floor, a second bracket pivoted to said opera seat rearwardly of the upper point of attachment of the forward bracket, and designed to be pivoted to the floor, said brackets being of different length from the seat to their lower ends, a member secured to one of said 70 brackets and extending toward the other, means on said other member for limiting the up and down movement of said member, said member being composed of two parts longitudinally adjustable, the fore-and-aft 75 distances between the pivot points of the two brackets on the chair, and their pivot points at their lower ends being different. 80

Des Moines, Iowa, March 6, 1917.

FRANK FESSLER.
